UNITED STATES PATENT OFFICE.

OSCAR ANDERSON, OF LANCASTER, PENNSYLVANIA.

TEAT-CUP.

1,167,968.

Specification of Letters Patent. Patented Jan. 11, 1916.

Application filed September 5, 1914. Serial No. 860,483.

To all whom it may concern:

Be it known that I, OSCAR ANDERSON, a citizen of the United States, residing at Lancaster, in the county of Lancaster, State of Pennsylvania, have invented a Teat-Cup, 5 of which the following is a specification.

The method or improvement set forth in this specification relates to that class of milking machines in which the teat is subjected to suction and to intermittent squeezing. In machines of this type heretofore used it is necessary to use both a vacuum 10 and a pressure pump as well as one pipe line for vacuum and one for pressure and other parts in duplicate, to get satisfactory results.

The primary object of my invention is to eliminate the use of pressure pump, pipe line and other duplicate parts heretofore 20 used and also to create different degree of pressure on different teats at the same time from a constant pressure such as the atmospheric. By this arrangement my milking machine will be more applicable to different 25 cows, as all cows do not respond well to the same degree of squeezing of the teat when milked. Besides this the machine is simpler and easier to handle and requires less power to operate as will be understood.

30 My method consists in concentrating the atmospheric pressure or a low pressure on a large surface to act as a higher pressure on a smaller surface.

In teatcups heretofore used a small and 35 quite flexible rubber sleeve has been employed to squeeze the teat, so it has, when under pressure, taken the shape of the teat it inclosed, pressing equally on all sides. In that construction the atmospheric pressure 40 is insufficient to give satisfactory result so more than atmospheric pressure had to be resorted to.

In my method, I use in my preferred construction of the teatcup, a comparatively 45 stiff, yet flexible sleeve, which squeezes either directly or indirectly on the teat. The sleeve when under partial vacuum from inside, will collapse, but is so stiff as not to follow the shape of the inclosed teat, but 50 flattened out over it will present a much larger surface to the pressure from the outside thus increasing the pressure on the teat.

To avoid unnecessary waste of energy to 55 collapse the sleeve I reduce the thickness of

the wall on two opposite points lengthwise as will be explained hereafter.

My improvement is illustrated in accompanying drawing in which like numerals of reference indicate corresponding parts in 60 each of the several figures.

Figure 1 is a vertical sectional view of a teatcup taken at line C Fig. 2. Fig. 2 is a cross section taken at line A Fig. 1. Fig. 3 is a section like Fig. 1, showing the teat 65 squeezed. Fig. 4 is a cross section taken at line B Fig. 3.

In Fig. 1 *a*, is a rigid outer shell; *b*, is a flexible sleeve; *c*, is a preferably transparent funnel shaped bottom terminating in a duct 70 or nipple *c'*. At the top of shell *a*, is a rigid extension *d*, which is contracted at one end to form passage for the teat. On side of shell *a*, is a hose nipple *f*, for admitting suction and pressure alternately between 75 shell *a*, and sleeve *b*.

In assembling the teatcup, sleeve *b*, is placed inside shell *a*; the ends of sleeve *b* being thinner than the middle and of uniform thickness are turned over the ends of shell *a*, the bottom *c*, is then placed over the lower end and top piece *d*, over the upper; the ends of sleeve *b* are then turned over again as at *b'*. An independent and airtight joint is thus formed for 85 each end of the compartment between the shell and the sleeve in the simplest possible manner.

Shell *a*, is round in cross-section at its ends as far as sleeve *b* is folded over same 90 and between has the form shown in Figs. 2 and 4. Sleeve *b* may be cylindrical in its general outline as shown in Figs. 1 and 2, except a reduced thickness in its wall on opposite sides as at *g*.

In operation the teatcup is connected by a hose from duct *c* to a milk receptacle under partial vacuum. Nipple *f* is by a hose connected to a pulsator or means to alternately admit suction and atmospheric pressure between shell *a* and sleeve *b*. The cup is then placed under the end of the teat and suction turned on through both ducts *c* and *f*; the suction draws the teat into proper place in the cup. (The position of sleeve *b* 105 is shown in Figs. 1 and 2.)

When suction is cut off from nipple *f* and atmospheric pressure is admitted, sleeve *b* collapses over the teat as shown in Figs. 3 and 4. It will be noticed that the outside 110

surface of sleeve *b* is larger than the surface of the teat it squeezes. I have thus concentrated a low pressure on the outside of the sleeve to act as a higher pressure on the teat. By making the outside surface of sleeve *b* larger or smaller I can vary the pressure on the teat, from a constant outside pressure. The alternate application of suction and pressure through nipple *f* will alternately relieve and squeeze the teat thus draw the milk as will be understood.

Other features may be used in connection with this improvement. For instance, such as described in my Patent No. 1,113,943, Oct. 20, 1914.

I do not wish to limit myself to any precise construction to accomplish my object as set forth in this application.

Having described my invention I claim:

1. In a milking machine subjecting the teat to steady suction and intermittent squeezing, means for concentrating atmospheric pressure to give a greater effective squeezing pressure on the teat and means to intermittently relax said pressure by suction.

2. In a milking machine teatcup subjecting the teat to steady suction and intermittent squeezing, means whereby a low fluid pressure can be concentrated to give a greater proportionate degree of squeezing on the teat, and means to relax said squeezing by suction.

3. In a milking machine teatcup subjecting the teat to steady suction and intermittent squeezing, means within the teatcup, whereby the atmospheric pressure may be concentrated to give a greater proportionate degree of squeezing on the teat.

4. In a milking machine subjecting the teat to steady suction and intermittent squeezing, means adapted to convert a low outside pressure to a higher pressure on the teat and means to intermittently relax the squeezing without interrupting the steady suction on the teat.

OSCAR ANDERSON.
